WARNING OR SIGNAL LIGHT

Eugene J. Freeman, Canoga Park, Calif., assignor to
Gen-A-Matic Corporation, Van Nuys, Calif., a corpora-
tion of California

Application December 31, 1956, Serial No. 44,362

Term of patent 14 years

(Cl. D72—1)

Fig. 1 is a perspective view taken from the top, one side and one end of a warning or signal light embodying my new design;

Fig. 2 is a top plan view thereof;

Fig. 3 is a perspective view taken from a position diametrically opposite that of Fig. 1; and

Fig. 4 is a bottom plan view thereof.

I claim:

The ornamental design for a warning or signal light, as shown.
